APPARATUS FOR STRAIGHTENING CANS
AND THE FLANGES THEREOFAlfred Treff, Chicago, Ill., assignor to Continental
Can Company, Inc., New York, N. Y., a corpo-
ration of New York

Application June 6, 1945, Serial No. 597,751

3 Claims. (Cl. 153—48)

1

The invention relates generally to can feeding apparatus, and more particularly to apparatus for feeding cans into filling machines of the type disclosed in the copending application for U. S. Letters Patent Serial No. 495,886 filed by Paul E. Pearson and Alfred Treff on July 23, 1943 (Patent No. 2,433,061, granted Dec. 27, 1947), and it primarily seeks to provide novel means for engaging and straightening both the body and flange portions of any misshapen cans being fed into the filling machine.

It frequently happens that cans manufactured to receive products for the market become bent slightly out of shape, both in the open mouth and the outwardly extending flange thereof intended to form a part of the seam structures by which end closures are secured on the cans after the filling thereof. Obviously, such misshapen cans may seriously interfere with proper filling of the cans, or with the seam sealing thereof, and it is the purpose of the present invention to provide novel can straightening means engageable with the cans as they are being fed into the filling means and effective to reshape the open tops and also the flanges of any slightly misshapen cans so that all cans entering the filling machine will properly be seam sealed by the closing devices which may be embodied in the same machine or in an adjacent separate closing machine.

An object of the invention is to provide an apparatus of the character stated in which there is included means for moving the cans in equidistantly spaced relation over a definite path of travel, a carrier movable in timed relation to the can feeding means and having thereon a plurality of can straightening dies, and means for vertically reciprocating the dies as they are moving along in timed relation with the moving cans so that each die will enter a can, straighten the mouth portion thereof should it be misshapen, and then move out of said can.

Another object of the invention is to provide an apparatus of the character stated in which each straightening die includes a spring depressed straightening and stripping ring which is engageable with the top end of a can in a manner for straightening the flange thereof should the same be misshapen, and also for stripping the can from the die should it tend to move upwardly with the same as it is leaving the open mouth of the can.

Another object of the invention is to provide an apparatus of the character stated in which the can feeding means includes a rotary turret having equidistantly spaced peripheral pockets in

2

which the cans are moved, and in which the straightening dies are carried at the lower ends of vertically reciprocable plungers and are reciprocated by means of rollers attached to the plungers and engaging in the groove of a stationarily mounted actuator cam.

With the above and other objects in view that will hereinafter appear, the nature of the invention will be more clearly understood by reference to the following detailed description, the appended claims, and the several views illustrated in the accompanying drawings.

In the drawings:

Figure 1 is a plan view illustrating an apparatus embodying the invention, parts being broken away and in section.

Figure 2 is a vertical longitudinal section taken on the line 2—2 on Figure 1.

Figure 3 is a vertical cross section taken on the line 3—3 on Figure 1.

Figure 4 is an end elevation looking in the direction in which the cans are fed into the apparatus.

Figure 5 is an enlarged fragmentary sectional view showing a can straightening die lowered to the maximum depth into the open mouth or upper portion of a can.

Figure 6 is a view similar to Figure 5, the die being shown as moving out of the can and the stripper ring being in the process of stripping the can from the die.

Figure 7 is an enlarged fragmentary sectional view illustrating the plunger carrying rotor and the actuating cam, the straightener heads being removed from the plungers.

Figure 8 is a horizontal section taken on the line 8—8 on Figure 7.

Figure 9 is a detail horizontal section taken on the line 9—9 on Figure 2.

40 In the example of embodiment of the invention herein disclosed, the novel apparatus is adapted for feeding and reshaping or straightening cans while they are being fed to a filling machine such as a meat filling machine of the type shown in the copending application for U. S. Letters Patent, Serial No. 495,886, filed by Paul E. Pearson and Alfred Treff on July 23, 1943, now Patent No. 2,433,061. This improved apparatus includes a

45 can feeding means generally designated A, timing means generally designated B, transfer wheel generally designated C, a feed turret generally designated D having the can straightening means generally designated E cooperating therewith, and a second transfer wheel generally designated

F and which serves to feed the cans onto the main or filling turret G of the filling machine.

In the disclosed apparatus, there is included a main frame structure 5 to which a supplemental frame extension or table 6 is attached as at 7.

The frame structure 5 is equipped with a lower bearing 8 and an upper bearing 9, the latter serving to rotatably receive a shaft 10. The lower bearing 8 rotatably supports a hub or sleeve 11 of a casing part 12 having an apertured plate 13 fixed therein, said plate including a hub portion 14 which is secured to the previously mentioned shaft 10. The hub 11 is flange-secured as at 15 to a driver gear 16, and a sleeve 17 has rotatable bearing in the hub 11 and has a plate enlargement 18 secured to the lower end thereof within the casing part 12. A driver gear 19 is fixed on the upper end of the sleeve 17 and is adapted to have rotation imparted thereto from a gear rotatable with the main or filling turret generally designated G and forming part of the filling machine of the copending patent application hereinabove referred to.

The plate enlargement 18 is equipped with a ball seat 20 which is normally engaged by a ball 21 mounted in an aperture in the plate 13. Normally the rotation imparted to the sleeve 17 will be transmitted through the ball 21 and the plate 13 to the shaft 10 and to the sleeve 11 and gear 16, but should a jam occur in the apparatus, resisting rotation of the shaft 10 a predetermined amount, the ball 21 would be displaced from the aperture in the plate 13 by movement of the plate 18 relative thereto and would move the plate 22 longitudinally along the pin equipment 23 which holds the same against relative rotation, and against spring means which normally holds the plate 22 in the normal position illustrated in Figure 2.

It will be apparent that the plates 18, 13, 22 and the ball 21 and the plate recess 20 constitute one form of overload release means effective to permit relative movement of the parts without breakage should a jam occur in the apparatus. This overload release means, in itself, forms no part of the present invention, and it is to be understood that any acceptable form of overload release means may be employed. When the plate 22 is moved longitudinally by displacement of the ball 21 from its socket, it may act through thrust means 24 to actuate a control valve effective to initiate the operation of stop control means such as is disclosed in the copending application for U. S. Letters Patent hereinbefore referred to, and which is effective to stop the operation of the filling machine. The control valve 25 may be supported as at 26 on the frame structure 5, and, if desired, other manually operable stop controls 27 may be provided and connected with machine stopping devices associated with the filling machine (which are not disclosed herein since they form no part of the present invention).

The driver gear 16 meshes with and drives a gear 28 of like size secured on the lower end of the shaft 29 which is uprightly disposed and rotatable in a bearing 30 provided therefor in the frame extension 6. The gear 28 in turn meshes with a gear 31 of like size and which is secured on the lower end of an uprightly disposed shaft 32 which is rotatable in bearings 33 provided in the frame extension 6.

The shaft 29 has a circular can supporting table 34 keyed thereon, and also a hub 35 to which is removably and adjustably secured a turret 36, the adjustable attachment of the turret being

indicated at 37. The turret 36 is provided with a plurality of equidistantly spaced half pockets 38 in the periphery thereof, said pockets being adapted to receive and properly space cans being fed on their way to the main or filling turret G.

The shaft 10 is provided with a hub 39 to which a transfer wheel 40 is removably and adjustably secured as at 41. The transfer wheel 40 is provided with equidistantly spaced, radially projected fingers 42 which are effective to deliver the cans in suitably spaced relation onto the main or filling turret G in the manner illustrated in Figure 1.

The shaft 32 is equipped with a hub 43 to which a transfer wheel 44 is removably and adjustably secured as at 45, said wheel being equipped with equidistantly spaced radially projecting feed fingers 46 as in the case of the first mentioned transfer wheel 40. The transfer wheel 44 serves to deliver the cans in equidistantly spaced relation to the receiving pockets 38 of the turret 36. See Figures 1 and 2.

An arcuate feedway 47 is provided on the frame extension 6 in position for cooperating with the transfer wheel 40, and said feedway is flanked by stripper fingers 48 straddling the peripherally pocketed turret 36 and with an arcuate guide portion 49 disposed in concentric relation to the periphery of said transfer wheel.

The frame extension 6 also is provided with an arcuate feedway 50 in position for cooperating with the transfer wheel 44, and this feedway also is flanked by a concentric guide portion 51 opposite the transfer wheel 44, and by fingers 52 straddling the peripherally pocketed turret 36.

It will be apparent by reference to Figure 1 of the drawings that a similar arcuate guide Y is disposed in concentric relation about the peripherally pocketed turret 36 and over the rotary can supporting table 34, this guide means also terminating with transfer wheel straddling fingers at the respective ends thereof. In this manner a continuous, reversely arced feedway for the cans is formed about the transfer wheel 44, the turret 36, and the transfer wheel 40 leading to the main or filling turret G in the manner clearly illustrated in Figure 1.

As the cans are initially fed into the apparatus they are fed over a long infeed way 52 provided on the frame extension 6 and defined at one side by an upright wall 54, and at the other side by the timing screw 55 which is rotatably mounted in bearings 56 at the respective ends thereof.

The cans are fed into the apparatus by a block chain 57 which passes over a driver sprocket 58 secured on a shaft 59 rotatable in bearings 60 in the extension 6 and which is driven by a bevel gear couple 61 from the shaft 32. The chain driven by the sprocket 58 also passes over an idler sprocket 62 at the delivery end where the cans pass into the arcuate feedway 50, and over an idler sprocket 63 on an idler shaft 64 which is rotatable in a bearing 65 in said frame extension, and over a tightener sprocket 66 which is adjustably mounted as at 67.

A gear 68 mounted on the shaft 64 drives a gear 69 on a shaft mounted in a bearing 70 and which is connected by a bevel couple 71 with the previously mentioned timing screw 55.

A lard spray nozzle 72 is supported on a rigid standard 73 secured as at 74 on the frame extension 6, and this spray nozzle operates in a manner described in the previously mentioned

copending application for spraying lard into each can as it is moved along by the block chain 57.

A guard 75 may be mounted over the transfer wheel 44 and pivotally supported as at 76 so that it can be retained in the effective position illustrated in Figures 1, 2 and 3 of the drawings and swung away whenever it is desired to render said transfer wheel accessible.

Beside the rotary table 34 the frame extension 6 is equipped with a bearing 77 in which a standard 78 is secured. This standard carries an arm 79 at its upper end in position for extending over the rotary table 34. The arm is equipped with a supporting bracket 80 from which is stationarily suspended the cam 81 having an actuator groove in its periphery formed to include a dwell portion 82 extending approximately 240° about the circumference thereof, and a depressed portion 83 extending about the remainder of the cam circumference.

Beneath the cam 81 and above the rotary table 34 a rotor 84 is keyed to the shaft 29 as at 85. The rotor is provided with a plurality of equidistantly spaced, uprightly disposed bearings 86, one such bearing being provided for each of the peripheral pockets 38 in the can feeding turret 36.

A carrier plunger 87 is vertically reciprocable in each of the rotor bearings 86, and each plunger is equipped with an actuator roller 88 engaging in the groove 82, 83 in the periphery of the fixed cam 81. Each plunger roller is mounted on a supporting pin extending through a vertical longitudinal slot 89 in the respective bearing 86. In order to facilitate the mounting and removal of the plungers 87, each rotor bearing 86 is provided with a removable wall portion 90.

Each carrier plunger is equipped with a mounting head 91 at its lower end to which a straightener head 92 is removably attached by screws 93. It will be apparent by reference to Figures 2, 5 and 6 of the drawings that the lower extremity of each head 92 is reduced in size to provide a straightener plug or die portion 94 shaped to snugly enter the open top of a can, and the bottom edges of each die or plug are bevelled as at 95 to facilitate entry of the same into the cans as they are being fed about in the pockets 38 of the turret 36.

The formation of the dies or plug portions 94 at the lower ends of the straightener heads 92 also provides abutment shoulders 96, and each die head is equipped with outwardly extending flange portions 97 which are apertured to receive a plurality of ring supported plungers 98 having adjustable abutments 99 at the upper ends thereof and above said flange portions, said plungers being secured at their lower ends to a stripper ring 100 having the main body portion 101 thereof slidably encircling the respective die or plug portion 94 and terminating downwardly in a reshaping edge 102 engageable with the outwardly extending flanges 103 of cans X for suitably straightening the same prior to the feeding of the cans into the filling machine. Each stripper ring supporting plunger 98 is surrounded by a compression spring 104 between the head flange portions 97 and the respective ring flange 100, and the springs serve to yieldably hold the stripper rings in the lowered position illustrated in Figure 2 of the drawings and determined by adjustment of the abutment means 99.

In the operation of the apparatus the cans X are fed into the apparatus in processional order as illustrated at the left in Figure 1, the block

chain 57 serving to convey the cans through the feedway 53, and the cans being fed onto the feedway 53 by any suitable means (not shown). As the cans move toward the timing screw 55 each thereof will have lard sprayed thereinto by the nozzle 72 in the manner previously described, and when the cans engage the timing screw 55 they will be suitably spaced thereby and positioned for being successively engaged by the feed fingers on the transfer turret 44 and moved over the arcuate feedway 50 and into the receiving pockets 38 of the feed turret 36.

As the cans are fed about by the table 34 between the peripheral pockets 38 and the arcuate guide Y the cam groove portion 83 becomes effective to lower each plunger 93 and the die 94 carried thereby into the underlying can X. As previously stated, the plunger depressing portion 83 of the cam extends about approximately 120° of the circumference of the cam, and this depressed portion of the cam groove is so placed that the dies 94 will be lowered into the cans and lifted out of said cans while they are being fed along by the turret 36 and accurately guided by the guide Y and before the transfer wheel 40 commences the transfer feeding of the cans through the arcuate feedway 47. In other words, the movement of the dies into and out of the cans is completed during travel of the feed turret 36 through approximately 120°.

As each die 94 is lowered into a can X, it will be guided accurately thereinto by the bevelled lower edge portions 95 and will serve to straighten the can and restore it to the designed dimensions of its initial manufacture. As each die enters the respective underlying can X, the stripper ring 101 will engage the can flange 103 and will slide upwardly over the die portion 94 of the straightening head against the action of the springs 104 until the upper surface of the ring engages the abutment shoulder 96, at which time the lower edge extremity 102 of the ring will become a fixed abutment edge effective to straighten any upwardly bent or misshapen portions of the can flange 103 in the manner clearly illustrated in Figure 5.

As each die portion 94 starts to recede upwardly out of the respective can X the stripper ring will remain in contact with the can flange by action of the springs 104 and will serve to overcome any tendency of the can to move upwardly with the die, or in other words strip the can from the die in the manner illustrated in Figure 6.

While one form of the invention has been shown for purposes of illustration, it is to be clearly understood that various changes in the details of construction and arrangement of parts may be made without departing from the spirit and scope of the invention as defined in the appended claims.

I claim:

1. In apparatus of the character described, means for feeding open top cans in equidistantly spaced relation over a definite path of travel, a carrier movable over the path of travel of the cans, a plurality of straightening dies supported on said carrier and each including a die plug conforming in shape to the open top of a can throughout the whole perimeter thereof and snugly and deeply slidably into such can tops, and means for vertically reciprocating the die plugs through a predetermined definite stroke bearing fixed relation to the open tops of the fed cans and in timed relation to the travelling cans for moving a die plug into and then out of the open top of

each can passing beneath the carrier, thereby to reshape any misshapen cans throughout the whole perimeter of the open top thereof, each said die plug having a spring depressed stripper ring thereon engageable with the top of a can and effective for stripping from said plug any can tending to move upwardly therewith as the die plug is withdrawn upwardly from the open top of said can, and also an abutment means limiting free downward sliding movement of the die plug through the stripper ring and so placed with relation to the open tops of fed cans as to make the bottom of the ring effective to engage and straighten misshapen can flanges on cans in which the die plug slidably engages in straightening contact.

2. In apparatus of the character described, means for feeding open top cans in equidistantly spaced relation over an arcuate path of travel, a rotor movable in part over said path, straightening die plugs vertically-reciprocably mounted on said rotor in equidistantly spaced relation and conforming in shape to the open top of a can throughout the whole perimeter thereof and snugly slidable in such can tops, and means for reciprocating said die plugs through a predetermined definite stroke bearing fixed relation to the open tops of fed cans and in timed relation to the passing therebeneath of the cans so as to cause a die plug to move deeply into and then out of the open top of each can passing therebeneath and by this means straighten all misshapen cans fed beneath said rotor, each said die plug having a spring depressed stripper ring thereon engageable with the top of a can and effective for stripping from said plug any can tending to move upwardly therewith as the die plug is withdrawn upwardly from the open top of said can, and also an abutment means limiting free downward sliding movement of the die plug through the stripper ring and so placed with relation to the open tops of fed cans as

5 10 15 20 25 30 35 40

to make the bottom of the ring effective to engage and straighten misshapen can flanges on cans in which the die plug slidably engages in straightening contact.

3. Apparatus as defined in claim 2 in which each die is carried by a plunger having a roller projecting therefrom, and the reciprocating means comprises a stationary grooved cam into the groove of which all said rollers project and travel, the die plugs and the rings slidable thereon being non-circular in shape and bearing predetermined definite relation to the can feeding means so that the plugs will properly enter and fit the cans, and there also being included on said plungers and rotor cooperating lug and slot means effective to cause the plungers and rings to travel in a rectilinear path for maintaining their predetermined definite relation to the can feeding means.
